UNITED STATES PATENT OFFICE

2,335,369

APPARATUS FOR SEPARATING GENUINE
FROM SPURIOUS COINSFred E. A. Wallin, University City, Mo., assignor
to N. Marshall Seeburg, Chicago, Ill.

Application March 16, 1942, Serial No. 434,861

14 Claims. (Cl. 194—100)

This invention relates to apparatus for separating genuine from spurious coins and it is particularly concerned with apparatus for separating genuine United States nickels or United States and Canadian nickels from spurious simulations thereof.

The operation of the present invention depends upon the fact that the metal of a United States nickel coin appears to constitute with most metals a thermocouple providing a much higher voltage than any other known metal or alloy, together with similar metals. A Canadian nickel coin is made of pure nickel and it is found that it provides, with most other metals, thermocouples giving slightly less voltage than do United States nickels. As will hereinafter be pointed out, my apparatus may be readily adapted to accept United States nickels only and to reject all other coins and tokens or it may be adjusted so that it will accept United States and Canadian nickels and reject all other coins.

One of the objects of the present invention is to provide an improved apparatus for separating genuine from spurious coins in which the coin is automatically constituted as one element of a thermocouple, being forcibly pressed against another thermocouple element for a limited period of time.

A further object of the invention is to provide in such an apparatus, means for preventing movement of a coin away from testing position for a controlled period of time and coin pressing means associated therewith, arranged to be effective before the coin releasing means.

A further object of the invention is to provide an apparatus for separating genuine from spurious coins in which a plurality of coins may be inserted simultaneously or almost simultaneously and in which they are tested automatically by the apparatus one after the other.

Other objects, advantages and capabilities of the present invention will appear from the following description of preferred embodiments thereof taken in conjunction with the accompanying drawings, in which:

Fig. 1 is a side elevation of the separating apparatus installed in a vending cabinet;

Fig. 2 is a sectional detail thereof taken on the line 2—2 of Fig. 1;

Fig. 3 is a plan view of the separating apparatus;

Fig. 4 is a fragmentary side elevation showing the manner in which a plurality of coins are received thereby;

Fig. 5 is a fragmentary sectional plan view on an enlarged scale taken on the line 5—5 of Fig. 4;

Fig. 6 is a wiring diagram;

Fig. 7 is a side elevation of the separating apparatus as viewed in a direction which is opposite to that from which Fig. 1 is taken, the mecha-

nism being shown in condition for the reception of a coin;

Fig. 8 is a similar view partly broken away, the mechanism being shown in its position during the testing of a coin; and

Fig. 9 is a perspective view of the heated contact and heater assembly.

Referring to the drawings, the reference numeral 10 designates a housing which may be part of a vending machine, coin-controlled phonograph, or other coin-controlled device. The housing 10 is provided with a slot 11 adapted to receive a United States nickel or a United States and Canadian nickel. The slot 11 leads into a chute 12 which may suitably be constituted by a wall of a frame 13 and a swinging plate 14 together with suitable lugs and abutments which guide an inserted coin of appropriate size downwardly until it seats upon two pins 15 and 16 which extend across the chute 12 through suitable openings in the walls 13 and 14.

The plate 14 is pivotally mounted on the wall 13 by means of lateral extensions 17. These extensions 17 are provided with forwardly turned extremities which extend into suitable slots in the wall 13. Pins 18 extend from the wall 13 through openings in the extensions 17 and carry at their outermost or rearmost ends washers 19.

Coil springs 20 which engage the washers 19 and the extensions 17 serve normally to hold the plate 14 in juxtaposition to the plate 13 so as to provide a coin slot therebetween. The plate 14 is provided with a cam-shaped projection 21 which extends forwardly through an opening in the wall 13. This cam-shaped projection 21 is adapted to be engaged by a cam 22 carried by a lever 23 pivotally mounted on the front side of the wall 13.

The pivoted lever 23 can be depressed from the exterior of the housing 10 by means of a button 24. This button engages a forwardly extending lug on the lever 23, the arrangement being such that when the button 24 is pressed downwardly, the lever 23 is swung downwardly and the cam 22 engages the cam-shaped projection 21 thus swinging the plate 14 rearwardly.

Above the pin 15 the plate 14 carries an arm 25 which extends over the pin 15 towards the pin 16 so as to be in register with a coin sitting upon the pins 15 and 16. The arm 25 extends forwardly and inwardly and is normally located forwardly of the chute 12, a suitable recess 26 being provided in the wall 13 to receive it.

It will readily be understood that if a coin for some reason remains upon the pins 15 and 16 it may be retrieved by the depositor by merely depressing the button 24. This causes the plate 14 to swing rearwardly and it causes the arm 25 to carry the coin off the pin 15 so that it may fall downwardly into a discard chute 27.

The coin may be directed into the discard chute

27 by means of a flange 28 which extends laterally in inclined direction substantially between and below the pins 15 and 16. The forward edge of the flange 28 is spaced from the wall 13 a sufficient distance to enable coins to drop normally downwardly from the pins 15 and 16 when the pin 16 moves outwardly.

Such coins are adapted to engage a gate 29 which is slightly below and parallel to the flange 28 or if this gate is withdrawn, the coins may fall directly through a coin chute 30 for the genuine coins, this chute being immediately below the gate 29.

The gate 29 is normally held in coin-rejecting position by means of a spring 31. It is moved into coin-accepting position by means of an electromagnet 32 which is arranged to attract a rearwardly extending flange 33 on the gate 29. The gate 29 is pivotally mounted on the plate member which cooperates with the wall 13 to provide the chute 30. The electromagnet 32 is suitably mounted by means of a bracket 34 upon the rear wall of the plate 13.

Also mounted on the rear wall of the plate 13 are lugs 35, 36 and 37 which engage a flashlight cell 38 or other suitable source of direct current. The lug 35 is grounded to the chassis and is adapted to engage the central terminal of the cell 38. The lug 36 resiliently engages the side of the cell 38 and forces it against the side flange of the plate 13.

The lug 37 is insulated from the wall 13. This lug engages the bottom or zinc wall of the cell 38 and it is connected to one side of the electromagnet 32. The other side of the electromagnet is connected to a stationary contact 39 of a sensitive relay 40. This contact is adapted to be engaged by a movable contact 41 which is carried by the moving coil 42 of the relay.

The coil 42 is connected by conductor 43 to the plate 13 which serves as a ground. The conductor 43 is also electrically connected to the moving contact 41. The other side of the coil 42 is connected by conductor 44 to a thermocouple 45, the other side of which is connected by conductor 46 to the pin 15.

The relay 40 may suitably have a base 47 of insulating material provided with prongs which connect into a socket 48 mounted on the wall 13.

The pin 15 is suitably a substantial rod of silver which is mounted on the upper end of a copper rod 49. The rod 49 is mounted on the forward side of the plate 13, the pin 15 extending rearwardly therefrom through suitable openings in the walls 13 and plate 14. The copper rod 49 is rigidly supported by brackets from an insulating plate 50 which extends forwardly from the wall 13.

The copper rod 49 extends through a heater resistor 51 of the ceramic type. Opposite ends of the resistor 51 are connected to power leads 52 which are connected to a plug 53 adapted to be plugged into any suitable utility outlet.

One of the leads 52 is connected to one side of a solenoid 54 which is mounted on the front of the plate 13. The other side of the solenoid is connected through a switch 55 to the other power lead 52.

The switch 55 may suitably be in the form of a couple of leaf contacts normally in separated relation. The pin 16 is constituted by a horizontal portion at the upper end of a rod 56 which is pivotally mounted on a bracket 57 carried by the plate 13. The bracket 57 may in fact be the

same bracket which carries the leaf contacts of the switch 55.

In an intermediate position the rod 56 has a horizontal portion which carries a circumambient insulating tube 58 normally in engagement with one of the leaves of the switch 55. The resilience of this leaf forces the pin 16 towards the pin 15, the pin 16 normally bearing against the edge of the opening in the wall 13 through which it passes.

When a coin is dropped through the slot 11 so that its drops down into engagement with the pins 15 and 16, the pin 16 is moved away from the pin 15 to an extent which is limited by the presence of an adjacent sector 59. The limited movement permitted for the pin 16 to engage the sector 59 is sufficient to close the switch 55 but is insufficient to permit the coin to drop past the pins 15 and 16.

It will readily be understood that when a coin engages the pins 15 and 16 and forces the pin 16 away from the pin 15, the circuit of the solenoid 54 to the power lines is completed and this solenoid is energized.

The armature of the solenoid 54 is biased upwardly by a spring 60 connected to the armature and to a bracket on the front side of the plate 13. Normally the armature is in its uppermost position but when the solenoid is energized, the armature is sucked down against the tension of the spring 60.

The sector 59 is integral with an arm 61 which carries at its outermost end a weight 62. The weight 62 is pivotally mounted near the sector portion by means of a shaft 63. This shaft is provided with bearings in two plates 64, 65, which are mounted in spaced relation upon the front of the plate 13.

The plates 64, 65 serve as the frame for a train of clockwork gearing 66 which includes a pinion on the shaft 63. The train of gearing terminates in a flywheel 67. The gear ratios of the train of clockwork gearing is such that a slow movement of the system 59, 60, 61 and 62 necessitates a very rapid movement of the flywheel 67. Consequently, the inertia of the flywheel provides a delay for the movement of the sector 59 under the influence of the weight 62.

It will of course be understood that any other suitable delay means may be employed. Thus, instead of the flywheel 67, I may provide vanes adapted to operate on the basis of air resistance. Furthermore, instead of the train of clockwork gearing, I may employ a dashpot or any other suitable equivalent delay creating means.

It will readily be understood that when the solenoid 54 is energized and its armature moves down promptly, the weight 62 tends to swing the sector 59 upwardly, clear of the pin 16. As pointed out before, this takes an appreciable time, such as a second or half a second, and during that period of time the coin is held under test in engagement with the heated contact pin 15.

A lever 68 is pivotally mounted on the front side of the wall 13 and is biased downwardly by a spring 69. The free extremity of the lever 68 bears against the upper end of the armature of the solenoid 54. The spring 69 is sufficiently strong so that when the solenoid 54 is deenergized, its armature, the weight 62, and the lever 68, are moved upwardly.

At an intermediate position the arm 68 carries a rearwardly projecting pin 70 which extends through an opening 71 in the plate 13 into alignment with the coin chute 12. The pin 70 is

normally located out of the path of a coin moving downwardly through the chute 12 into engagement with the pins 15 and 16. When, however, the solenoid 54 is energized and its armature immediately moves downwardly, the lever 68 follows it under the influence of the spring 69 and the lever 68 is arrested by engagement of the pin 70 with the coin under test.

The spring 69 is then effective to press the coin strongly against the heated contact pin 15. After the pin 70 has thus engaged the coin under test, the weight 62 moves the sector 59 clear of the pin 16 and thereupon the coin is moved swiftly away from test position by its own weight and by the pushing action of the pin 70.

Thus, the coin under test is maintained for a distinct interval in contact with the heated contact pin 15 and consequently adequate time is provided for the actuation of the gate 29 in the event that the coin is genuine. The thermocouple 45 is constituted by a nickel wire 72 which is connected to the conductor 44 and a copper wire 73 which is mounted on the lower end of the rod 49. The wire 73 is sufficiently long so that a temperature substantially lower than that of the contact pin 15 prevails at its point of connection with the nickel wire 72. The wire 72 is sufficiently long so that the temperature at its two ends is radically different.

The thermocouple 45 creates a back E. M. F., that is, it creates a voltage which opposes the voltage between the coin and the heated contact 15. The provision of this or other equivalent means for providing a back E. M. F. is described and claimed in my copending application Serial No. 329,675, filed April 15, 1940, and it must be understood that any of the means described in that application may be substituted for the specific means here described.

It will be understood that this back E. M. F. may be made smaller than the E. M. F. produced by a genuine coin in engagement with the heated contact 15 in any of a great number of ways. Thus, the temperature of the thermocouple 45 may be substantially less than that of the pin 15 or the metals or alloys which constitute the thermocouple 45 may be definitely selected, so that at the prevailing temperature of the thermocouple 45, be it higher or lower than that of the pin, the back voltage provided by the thermocouple 45 is less than that produced by a genuine coin and the heated contact pin 15.

It will readily be understood that if a spurious coin or slug is inserted, it constitutes, with the heated contact 15, a thermocouple of very inferior voltage characteristics. In that event the back E. M. F. produced by thermocouple 45 may be the greater and the flow of current through the relay 40 is in the opposite direction than that resulting from a genuine coin. Thus, instead of the contact 41 moving towards the contact 39, it will move in the opposite direction, which movement is limited by a stop 74.

Any suitable metals may be employed for the pin 15, for the rod 49, and for the elements 72 and 73, and the invention is not intended to be limited to the metals which have been previously referred to. Thus, the pin 15 and the rod 49 may be of silver, copper, brass, iron, stainless steel, or indeed any metal or alloy other than that of the alloy or metal of the coins which are to be tested. The same applies to the metals of the thermocouple 45. Thus, the metal 73 may be copper, silver, stainless steel, etc., and the metal

72 may be nickel, chromium, German silver or any other suitable metal. The principal point is that the E. M. F. produced by the thermocouple 45 should be opposite in voltage to that produced between the pin 15 and a genuine coin. The two voltages should be as close to each other as sensitivity of the relay 40 will permit.

In operation the plug 53 is plugged into any suitable outlet and the heater resistor 51 is heated to bring the temperature of the contact pin 15 to a desired temperature which may suitably be about 250° F. If the heater is not heated, no effective thermoelectric current can pass through the relay 40 and the gate 29 cannot be opened. Consequently, a genuine coin will be refused and it will pass down through the chute 27 to a return cup 75 in the same manner as a spurious coin or slug is returned as will hereinafter be described.

Assuming that a coin smaller than a United States or Canadian nickel is inserted, the coin hits the pin 15 and it also hits the pin 16, forcing it away from the pin 15 until it engages the sector 59. A smaller coin, such as a Mexican nickel, will pass the pins 15, 16, and will be returned to the return chute 27, the gate 29 being closed.

If a genuine coin is inserted, it hits the pin 15 and the pin 16, moving the pin 16 away from the pin 15 until it engages the sector 59. This closes the switch 55 and the solenoid 54 is energized, its armature moving downwardly immediately. The arm 68 under the influence of the spring 69 likewise immediately moves downwardly, following the armature of the solenoid 54 until its pin 70 engages the upper side of the genuine coin, forcing it firmly against the heated contact pin 15.

The heated contact pin and the genuine coin 40 constitute a thermocouple of very considerable voltage. This voltage is greater than and opposite to the voltage produced by the thermocouple 45. In the case of a genuine coin, this excessive voltage is sufficient to carry the arm 41 into engagement with the fixed contact 39. This completes the circuit from ground, battery 38, electromagnet 32, back to ground. The energization of the electromagnet opens the gate 29.

All this occurs while the weight 62 is swinging 50 downwardly towards the armature of the solenoid 54. This downward movement carries the sector 59 clear of the pin 16 and the weight of the coin, together with the force supplied to it by the pin 70, moves the coin downwardly 55 towards the chute 30 past the open gate 29. After the coin has cleared the pin 15, the relay 40 opens and when the residual magnetism of the electromagnet 32 dies down, the gate 29 moves to closed position, this occurring after 60 the accepted coin has safely passed into the chute 30.

In the case of a spurious coin, the actuation of the pin 16, the solenoid 54, and the sector 59 is precisely the same. The only difference is 65 that the relay 40 is not closed. The current passing through its coil is either not sufficient to move the contact 41 into engagement with the contact 39 or is in the opposite direction so that the movable contact 41 is moved into engagement with the stop 74. In either event the gate 29 does not open and when the pin 16 is cleared by the sector 59, the spurious coin is forced downwardly so that it engages the closed gate 29 which diverts it into the discard chute 27.

A plurality of coins may be inserted in the

coin chute 12 and in this event the coins will be tested and either accepted or rejected one at a time and one after the other. The lowermost coin rests upon the pins 15 and 16 and when the solenoid 54 is energized, the pin 70 moves downwardly into engagement with its upper end and when the pin 70 is at its lowermost position, it is located in the path of the next coin in the chute 12 holding this coin out of contact with the pin 16. It is only after the sector 59 has moved back into position opposite the pin 16 that the pin 70 releases the next coin so that it may move into engagement with the pin 16.

The engagement of the second coin with the pin 16 moves this pin into engagement with the sector 59 and incidentally closes the switch 55 so that the energization of the solenoid and the completion of the testing operation with that coin is continued. It will of course be understood that the chute 12 may be of any desired length to accommodate any desired number of coins.

The coin chute 30 may be connected to any desired coin controlled mechanism. Thus, a switch 76 may be located in the path of the descending coin so that it will be closed by every coin which is accepted and descends through the genuine coin chute 30. This switch 76 may be employed for the release of any suitable coin-controlled mechanism, many of which are well-known in the coin-control art.

Although the invention has been described in connection with the specific details of a preferred embodiment thereof, it must be understood that such details are not intended to be limitative of the invention except in so far as set forth in the accompanying claims.

I claim:

1. In an apparatus for separating genuine from spurious coins, comprising a heated contact arranged to engage a coin and constitute therewith a thermocouple and means controlled by said thermocouple for determining the disposition of the coin, in combination, means for holding a coin in a testing position in engagement with said heated contact, automatic means for actuating said holding means to effect release of the coin from said position, and time delay means associated with and exclusively controlling the operation of said automatic means whereby the coin is maintained in testing position for a definite interval of time.

2. In an apparatus for separating genuine from spurious coins, comprising a heated contact arranged to engage a coin and constitute therewith a thermocouple and means controlled by said thermocouple for determining the disposition of the coin, in combination, means including the heated contact and a movable supporting member for holding the coin in testing position, means normally limiting the movement of said movable supporting member, automatic means for rendering said limiting means ineffective, and means controlled by limited movement of said movable supporting member for actuating said automatic means after the coin has been in testing position for a definite interval of time.

3. In an apparatus for separating genuine from spurious coins, comprising a heated contact arranged to engage a coin and constitute therewith a thermocouple and means controlled by said thermocouple for determining the disposition of the coin, in combination, means including the heated contact and a movable supporting mem-

ber for holding the coin in testing position, means normally limiting the movement of said movable supporting member, automatic means for rendering said limiting means ineffective, means controlled by the limited movement of said movable supporting member for actuating said automatic means, and time delay means therefor whereby said limiting means are made ineffective a definite interval after the coin has reached testing position.

4. In an apparatus for separating genuine from spurious coins comprising a heated contact arranged to engage a coin and constitute therewith a thermocouple and means controlled by

15 said thermocouple for determining the disposition of the coin, in combination, means for holding a coin in a testing position in engagement with said heated contact, automatic means for engaging a coin in said position and forcing same against said heated contact and said holding means, automatic means for actuating said holding means to effect release of the coin from said position, and time delay means associated with last said automatic means whereby the coin is released definitely after the engaging means have forced the coin against the heated contact.

5. In an apparatus for separating genuine from spurious coins comprising a heated contact arranged to engage a coin and constitute therewith

30 a thermocouple and means controlled by said thermocouple for determining the disposition of the coin, in combination, means including the heated contact and a movable supporting member for holding the coin in a testing position, automatic means for engaging a coin in said position and forcing same against said heated contact, means normally limiting the movement of said movable supporting member, automatic means for rendering said limiting means ineffective, and means controlled by limited movement of said movable supporting member for actuating both said automatic means in succession whereby the coin under test is forced against the heated contact and is thereafter released.

45 6. In an apparatus for separating genuine from spurious coins comprising a heated contact arranged to engage a coin and constitute therewith a thermocouple and means controlled by

50 said thermocouple for determining the disposition of the coin, in combination, means including the heated contact and a movable supporting member for holding the coin in a testing position, automatic means for engaging a coin in said position and forcing same against said heated contact, means normally limiting the movement of said movable supporting member, automatic means for rendering said limiting means ineffective, means controlled by limited movement of said movable supporting member for actuating both said automatic means, and time delay means for causing last said automatic means to operate after first said automatic means has forced the coin against said heated contact.

7. In an apparatus for separating genuine from spurious coins comprising a heated contact arranged to engage a coin and constitute therewith

65 a thermocouple and means controlled by said thermocouple for determining the disposition of the coin, in combination, a coin chute for receiving a plurality of coins to be tested, means for holding the lowermost coin in a testing position in engagement with said heated contact, automatic means for engaging a coin in said position and arranged to move into the path of the next coin in the chute, automatic means

for actuating said holding means to effect release of the coin from said position, and time delay means associated with last said automatic means whereby the coin is released definitely after the first said automatic means.

8. In an apparatus for separating genuine from spurious coins comprising a heated contact arranged to engage a coin and constitute therewith a thermocouple and means controlled by said thermocouple for determining the disposition of the coin, in combination, means including the heated contact and a movable supporting member for holding the coin in a testing position, a coin chute adapted to receive a plurality of coins and to locate the lowermost coin in said testing position, automatic means for engaging a coin in said position and forcing the same against said heated contact and against said supporting member, said automatic means being arranged to move into coin-blocking position above the coin in the testing position, means normally limiting the movement of said movable member, automatic means for rendering said limiting means ineffective, and means controlled by said limited movement of said movable supporting member for actuating both said automatic means in succession whereby the coin under test is forced against the heated contact and is thereafter released.

9. In an apparatus for separating genuine from spurious coins comprising a heated contact arranged to engage a coin and constitute therewith a thermocouple and means controlled by said thermocouple for determining the disposition of the coin, in combination, means including the heated contact and a movable supporting member for holding the coin in a testing position, a coin chute adapted to receive a plurality of coins and to locate the lowermost coin in said testing position, automatic means for engaging a coin in said position and forcing the same against said heated contact and against said supporting member, said automatic means being arranged to move into coin-blocking position above the coin in the testing position, means normally limiting the movement of said movable member, automatic means for rendering said limiting means ineffective, and means controlled by said limited movement of said movable supporting member for actuating both said automatic means, and time delay means for causing last said automatic means to operate after first said automatic means has forced the coin against said heated contact.

10. In an apparatus for separating genuine from spurious coins comprising a heated contact arranged to engage a coin and constitute therewith a thermocouple, a gate for determining the disposition of the coin, and electromagnetic means controlled by said thermocouple for actuating said gate, in combination, means for retaining a coin in testing position in engagement with said heated contact, a switch actuated by said retaining means, and electromagnetic means controlled by said switch for releasing said retaining means.

11. In an apparatus for separating genuine from spurious coins comprising a heated contact arranged to engage a coin and constitute therewith a thermocouple, a gate for determining the disposition of the coin, and electromagnetic means controlled by said thermocouple for actuating said gate, in combination, means for retaining a coin in testing position in engagement with said heated contact, a switch actuated by said retaining means, electromagnetic

means controlled by said switch for releasing said retaining means, and time delay means associated with last said electromagnetic means whereby the coin is retained in testing position 5 for a definite interval of time.

12. In an apparatus for separating genuine from spurious coins comprising a heated contact arranged to engage a coin and constitute therewith a thermocouple, a gate for determining the disposition of the coin, and electromagnetic means controlled by said thermocouple for actuating said gate, in combination, means including the heated contact and a movable supporting member for holding the coin in testing position, 10 means normally limiting the movement of said movable supporting member, a switch arranged to be closed by a coin in said testing position, automatic means for rendering said limiting means ineffective including a second electromagnetic means controlled by said switch, and time delay means associated with said limiting means whereby the movable supporting member is held in coin-retaining position for a definite interval of time.

13. In an apparatus for separating genuine from spurious coins comprising a heated contact arranged to engage a coin and constitute therewith a thermocouple, a gate for determining the disposition of the coin, and electromagnetic means controlled by said thermocouple for actuating said gate, in combination, means including the heated contact and a movable supporting member for holding the coin in a testing position, automatic means for engaging a coin in 30 said position and forcing same against said heated contact, means normally limiting the movement of said movable supporting member, automatic means for rendering said limiting means ineffective, electromagnetic means controlled by limited movement of said movable supporting member for actuating both said automatic means, and time delay means associated with last said automatic means whereby the same is caused to operate after first said automatic means 40 has forced the coin against said heated contact.

14. In an apparatus for separating genuine from spurious coins comprising a heated contact arranged to engage a coin and constitute therewith a thermocouple, a gate for determining the disposition of the coin, and electromagnetic means controlled by said thermocouple for actuating said gate, in combination, means including the heated contact and a movable supporting member for holding the coin in a testing position, a coin chute adapted to receive a plurality of coins and to locate the lowermost coin in said testing position, automatic means for engaging the coin in said position and forcing the same against said heated contact and against 50 said supporting member, said automatic means being arranged to move into coin-blocking position above the coin in the testing position, means normally limiting the movement of said movable member, automatic means for rendering said 55 limiting means ineffective, and electromagnetic means controlled by said limited movement of said supporting member for actuating both said automatic means, and time delay means associated with last said automatic means whereby the same is caused to operate after first said automatic means 60 has forced the coin against said heated contact.
